UNITED STATES PATENT OFFICE

JOHN M. SCHNEIDER, OF ALBANY, NEW YORK

STYPTIC PENCIL

Application filed April 30, 1929. Serial No. 359,260.

This invention relates to an improved styptic pencil such as is used as an astringent applicator for after shaving purposes and for treating cuts and abrasions on the face.

5 The usual styptic pencil as now marketed has certain defects which I regard as most unsatisfactory and unsanitary. With these objections in mind, I have evolved and produced an unusually simple and inexpensive 10 arrangement for overcoming such objections in a practical and dependable manner.

My idea consists in the provision of a structure which is characterized by an ornamental bottle constructed to provide a casing or enclosure for a styptic pencil which is suspended therein in a pendulous manner, whereby to maintain the pencil clean and dry and otherwise susceptible of more satisfactory use.

20 The particular details and their special association and arrangement will become more apparent from the following description and drawings.

In the accompanying drawings, wherein 25 like reference characters are employed to designate like parts throughout the same;

Figure 1 is a perspective view of the complete product of manufacture as made in accordance with the present invention.

30 Fig. 2 is a central vertical section through the same on a slightly enlarged scale, and

Fig. 3 is a horizontal sectional view, on the line 3—3 of Fig. 2.

In carrying out the invention, I provide 35 an ornamental enclosure in the form of a bottle, generally designated by the reference character 4. This may be of transparent glass or of opaque glass, whichever is desired, and it may be suitably colored for ornate purposes.

The bottle includes an outwardly flared and flat bottom 5, which constitutes a rest, and which serves to support the bottle in an upright position in the medicine chest or wall cabinet. The bottle is shaped to gradually

taper upwardly and is of a general rectangular cross sectional configuration as indicated at 6. There is a supporting or shoulder forming groove at 7 which merges into a cylindrical neck 8, which neck is threaded to accommodate a metal cap 8^a to be screwed on.

50 A styptic pencil 9 which is of ordinary materials, is connected with and suspended at 7, at the shoulder formed at the upper end of the pencil where the top portion is 55 larger than the shaft of the pencil itself. The grip of the pencil being formed in one molding of the ordinary styptic material.

The pencil as seen in Fig. 2 includes a conical or bevelled inner end portion which rests 60 in the correspondingly shaped seat of the neck 7.

65 Under this arrangement the pencil is suspended in the body portion of the bottle as seen in Fig. 2, where it is rendered dust-proof, moisture-proof, and maintained in good condition for expeditious use.

An article of this construction and arrangement is unique and quite sanitary. It is therefore regarded as a commercial practical 70 contribution to the art. It is thought, however, that the construction and features and advantages will be quite clear to persons skilled in the art to which the invention relates, for which reason a more lengthy description is regarded unnecessary.

75 Minor changes in the shape, size, and rearrangement of details, coming within the field of invention claimed may be resorted to in actual practice if desired.

80 Having thus described my invention, what I claim as new is:—

1. A holder for a styptic pencil comprising an transparent receptacle having an elongated chamber, in which the pencil is adapted 85 to be wholly inserted and housing an integrally formed inwardly directed annular rib adjacent one end of the chamber for separating the latter into separate communicating compartments for connecting the head 90

and shaft respectively of the pencil, said rib providing an annular seat for the head of the pencil.

2. A holder for a styptic pencil comprising a transparent receptacle having an elongated chamber, in which the pencil is adapted to be wholly inserted and comprising a transparent receptacle in one end of the chamber for providing separate compartments for receiving the head and shaft of the pencil respectively, said shoulder providing a seat for the head of the pencil for supporting the latter in a pendulous manner within the receptacle, and a cap closing the said head receiving compartment of the receptacle.

10 15 In testimony whereof I affix my signature.

JOHN M. SCHNEIDER.
